UNITED STATES PATENT OFFICE.

ANDREW S. LAWTON, OF BROCKTON, MASSACHUSETTS, ASSIGNOR TO MAWHINNEY LAST COMPANY, OF BROCKTON, MASSACHUSETTS, A CORPORATION OF MASSACHUSETTS.

PORTABLE WARDROBE.

Application filed October 3, 1924. Serial No. 741,351.

This invention relates to improvements in portable wardrobes. More particularly it relates to that type of wardrobe which is adapted to be set into the corner of a room, 5 affording a closet with hooks and shelves; but which can quickly and conveniently be entirely collapsed, moved to another house and there set up afresh.

Sundry devices have heretofore been proposed for the purpose thus stated; but none, so far as I am aware are satisfactorily adapted to the variations between walls and corners of rooms in which it may be desired to set up the device. These variations between 10 supposedly similar right angled corners of rooms in different houses occur either through irregularities in the carpentering or plastering of the house, or of the floor, or of the settling of the structure after being 15 built. It is therefore one purpose of the invention to make a portable wardrobe which shall fit with stable precision each and any such corner, so as to fill the space and if desired to have the firm backing of the plaster 20 wall on each side, while being at the same time instantly removable therefrom for collapse and portability, and without in any manner defacing or being attached to such wall. This is accomplished by providing a 25 firm, stiff top for the wardrobe which serves both as a horizontal strut portion of the frame, at the top of the uprights or legs, and as a cover, and which may serve as a 30 shelf, and which is extensible and capable 35 of being fixed in different degrees of extension according to the particular precise angle of the supposedly right angled corner in 40 which it is to be set.

In practice, in one of the forms illustrated, 45 the stiff top of variable area is made with a frame having four horizontal bars, comprising a middle bar bisecting the angle at the corner of a room; two side bars, one running along each side of the angle adjacent to the 50 wall, preferably both of these being hinged to the middle bar; and a fourth bar crossing the angle, intersecting all these three bars, and preferably fixed in length and secured to the outer end of the middle bar. Deep slots 55 are provided in the side vertical faces of the

middle bar and the fourth bar, into which are set stiff horizontal sheets of fibre or ply wood which are preferably carried rigidly on the side bars of the frame, the latter have fastening means for securing them to the 55 fourth bar at varying degrees of spread, the stiff sheets moving out or in with them and having their free edges always covered by being embedded in the middle and fourth bars. Thus an expandible, flat, stiff, removable top is provided which can serve as a 60 strut for keeping the angle sides spread, and for a cover for the wardrobe, and for a shelf on which articles may be laid. This top is supported preferably on three legs or uprights, comprising a rear one in the corner and two front ones near the walls, the front legs being severally connected to the rear leg by hinged cross bars which permit the 65 spreading of the front legs to different angular positions, for setting up and for collapse. 70

Another purpose of the invention is to provide a certainty of stability which I have found lacking in portable corner wardrobes previously proposed. I accomplish this by 75 the very simple device of making the middle rear leg, at the vertex of the angle, shorter than the others and making it extensible. This results in canting the whole wardrobe slightly backward into the corner, when it is thus set at shorter length; so as to get a full bearing of the sides of the top on the adjacent wall; and in letting the whole front stand plumb when this feature of adaptability of the wardrobe is not needed for the 80 particular room and corner where it is to be placed; and in the latter case it can stand plumb and secure, even though the floor is pitched a little toward or from the corner. 85 It is thus possible to adjust the wardrobe 90 so that it is standing on all three legs, on the floor; and yet is leaning back against the side walls of the room, at the top of the wardrobe, and thus is in a position of security, with each garment added to its contents making it the more secure and steady. 95

Other features of the invention provide for the use of rigid inextensible rods for holding a front cover curtain and for holding coat hangers and the like in the midst 100

of the closet, notwithstanding the essentially extensible character of the frame, thus providing economical and firm construction for these important details in a degree that could not be had if they were themselves extensible.

It is also the purpose of the invention to provide the other features of improvement which are shown in the apparatus described.

10 It is intended that the patent shall cover, by suitable expression in the appended claims, whatever features of patentable novelty exist in the invention disclosed.

In the accompanying drawings,

15 Figure 1 is a perspective of a wardrobe constructed in accordance with the principles of the present invention;

Figure 2 is a plan of one form of top for the wardrobe;

20 Figure 3 is an elevation in section on line 3—3 of Figure 2 showing the middle bar and portions of the cover boards;

Figure 4 is a plan of a top side bar with its associated cover board;

25 Figure 5 is an elevation in section on lines 5—5 of Figures 1 and 2, showing details of a front corner;

Figure 6 is an elevation in section on line 6—6 of Figure 2 showing details of the rear corner;

Figure 7 is an elevation in section on line 7—7 of Figure 2;

Figure 8 is a plan of a modified form of top;

30 Figure 9 is an elevation in section on line 9—9 of Figure 8; and

Figure 10 is a plan in section on line 10—10 of Figure 1, showing details of the rear leg construction.

40 Referring to the drawings, the wardrobe is of skeleton construction comprising a rear leg 10 for the corner of a room, and two front legs 12, 14 which stand close beside the walls, and from each of which horizontal cross bars 16 extend to hinged connections with the rear leg so that the front legs may be spread toward or from each other at about 90° angle to accommodate the divergence of the walls, or close together for collapse and portability. The upper of these cross bars, as well as the rear leg, are provided with hooks 18 upon which may be hung garments or other things to be stored in the wardrobe. On this frame is removably mounted a stiff top which serves as a strut between the legs and also as a cover for the contents, and from which a curtain may be hung across the front opening.

45 The top shown in Figures 2 to 7, comprises a frame having a middle bar 20 extending outward bisecting the corner angle; a front bar 22 crossing the angle and joined rigidly to the middle bar; and side bars 24 which connect the corner end of the middle bar with the extremities of the front bar. A

vertical hole at the rear of the middle bar, and similar holes at the forward ends of the side bars, receive pins 26 which rise from the tops of the three legs; and each side bar is pivotally attached to the middle bar by a 70 plate 28 fastened to the side bar with a portion overlapping the middle bar and turning about the shaft of a screw 30 thereon. The outer end of each side bar has a thumb screw 32 which extends through a slot 34 in a plate 36 rigidly mounted on the front bar. This is arranged to permit swinging of the side bar, and with it the front leg, about the rear leg and screw 30 as a pivot, to increase or decrease the angular spread of the wardrobe; 80 the whole being secured in the desired setting by the thumb screws. The pin holes may, if desired, be so placed in the side bars as to provide an overhang of the side bars beyond the base line corresponding to the 85 standard thickness of baseboard commonly found in houses and apartments. Rather deep slots 38 are provided in all the bars along their vertical faces which oppose one another and border the two triangular top 90 openings formed by the bars. Each such opening is closed by a light, rigid board 40, such as ply board or fibre board, which is secured in the groove along each side bar and extends loosely into the grooves of the 95 middle and front bars. As the side bar is swung away from the other bars, the board moves with it, but still remains within the grooves of the latter so that no opening in the top occurs. These boards may be sufficiently strong to support hooks depending within the wardrobe, and to enable the top as a whole to be used for a shelf.

100 There is mounted on the forward face of the front bar 22 a rigid rod 42 for holding a curtain 44 which can be slipped to one side or the other or drawn across the front to cover the wardrobe contents. A lid 46 hinged at the top of the front bar swings as a hood over the curtain rod, protecting it 110 and the rings and curtain top from dust and giving a finished appearance to the forward edge of the top.

105 The top disclosed in Figures 8 and 9 is a modification of that already described, in 115 that it has no middle bar and only a single board 40^a for the top covering. This is fastened to the front bar 22 and extends loosely within deep grooves 38^a formed in the two side bars 24^a. As the latter are adjusted away from each other, about a pivotal connection 48 at their corner ends, to fit against the walls of the room adjacent to the corner, they move somewhat away from the cover board, but not far enough to withdraw 120 the edges of the latter entirely from their grooves. The amplitude of the provision for adjustment is seen clearly in Figure 9, where the side bar is shown in its extreme position of spread. The engagement of the thumb 125

screw 32 with the end of the slot 34 in the corner plate 26 prevents complete withdrawal of the cover board from its groove in the side bar.

5 In placing the wardrobe in the corner of a room it is desirable to have it stand on its three legs and where feasible to have its top side bars rest against the walls. Because of the variations in divergence of room walls 10 and in the level of the flooring, encountered in practice, some corners being less than a right angle and others being more, and the floor at the corner being sometimes higher and sometimes lower than it is along the 15 walls, the present invention provides a wardrobe which is adapted to accommodate itself to whatever conditions it encounters. In setting it up, the top is assembled and placed upon the pins 26 projecting from the tops 20 of the legs, the thumb screw nuts 32 being backed off so that the side bars can swing about the pivotal connections with the middle bar, as in Figure 2, or between themselves, as in Figure 8. The wardrobe is then 25 placed with its rear leg in the corner, and with its front legs against the walls or base boards of the room. The rear leg 10 is shorter than the others, and is made extensible in height to a length greater than that 30 of the others, by having a sleeve 50 at its end, adjustable along the leg, there being a vertical slot 50' in the sleeve and a thumb screw 32 projecting through it from the leg for fastening the sleeve at any desired position. 35 With the front legs in place the wardrobe may be tipped rearward until the inner end of the middle bar of the top rests in the corner, either against the plaster or just clearing it, as desired. The sleeve on the rear leg is then adjusted to stand on the floor and carry the weight with the top in this position; and the side bars are swung outward until they rest against the walls. When thus positioned the thumb nuts are tightened. 40 The wardrobe is now in place, firmly standing on its three legs and with its top fitting against the walls of the room. Garments can now be hung on the several hooks or suspended from a rigid rod 52 depending from 45 the middle bar, as seen in Figure 1, or upon a similar support on the under side of the one-piece board cover 40^a of Figure 8, or otherwise placed. Wherever placed the weight of the garments tends to maintain 50 the wardrobe without tilting or tipping from its original position. If preferred the rear post may be arranged to rise vertically from the floor at the corner of the base board thus keeping all uprights plumb, whether the 55 floor be precisely level or not, and yet the spreading of the front legs to the base boards will hold the whole steady; but in general it is not necessary to have the legs plumb for the flowing lines of the curtain cover dis- 60 semble any minor departure from strict ver-

ticality. Hence it is possible to set up the wardrobe satisfactorily even without using the rear leg adjustment, but merely resting on that leg in its shortest form, in which case all parts are firmly supported on floor, base 70 boards and plaster walls.

I claim as my invention:

1. A portable wardrobe adapted to be set in the corner of a room, comprising a frame having a rear corner leg and two front wall 75 legs, and a top comprising a stiff cover extensible angularly and mounted thereon; the said rear leg being shorter than the front legs, thereby permitting the wardrobe to be set with its three feet on the floor and the 80 edges of its top against the walls.

2. A portable wardrobe adapted to be set in the corner of a room, comprising a frame having a rear corner leg and two front wall 85 legs, and a top mounted thereon; the said rear leg being adjustable in length, for canting the wardrobe to hold its top against the walls while its feet are on the floor.

3. A portable wardrobe adapted to be set in the corner of a room, comprising a frame 90 having legs and a top mounted thereon; the said top having a frame with side members pivotally supported at their corner ends and a stiff front cross member connecting the front ends of said side members, and fastening means at the junction of a side member and the front member, permitting fixing of the side members in adjusted positions about their pivots.

4. A portable wardrobe adapted to be set 100 in the corner of a room, comprising a frame having legs and a top mounted thereon; said top having a frame comprising a middle bar bisecting the corner angle, a front bar crossing the angle and engaging the middle bar, 105 and movable side bars pivotally secured to the corner end of the middle bar and adjustably attached to the extremities of the front bar.

5. A portable wardrobe adapted to be set 110 in the corner of a room, comprising a frame having legs and a top mounted thereon; said top having a frame comprising a middle bar bisecting the corner angle, a front bar crossing the angle and engaging the middle bar, 115 movable side bars pivotally secured to the corner end of the middle bar and adjustably attached to the extremities of the front bar, and closure boards supported by said bars having a rigid engagement with one and a 120 sliding engagement with another of said bars.

6. A portable wardrobe adapted to be set 125 in the corner of a room, comprising a frame having legs and a top mounted thereon; said top having side members pivotally mounted at the corner, and a front member having connections with the front ends of said side members permitting said side members to be 130 swung about their pivots, and means limit-

ing the degree of said swing to adjustment dimensions approximating a right angle between the side members.

7. A portable wardrobe adapted to be set in the corner of a room, comprising a frame having a rear corner leg and two front wall legs, and a top mounted thereon; the said rear leg being adjustable in length, for cant-

ing the wardrobe to hold its top against the walls while its feet are on the floor, and said top being extensible angularly to accommodate variations in wall divergence. ¹⁰

CERTIFICATE OF CORRECTION.

Patent No. 1,663,949.

Granted March 27, 1928, to

ANDREW S. LAWTON.

It is hereby certified that error appears in the printed specification of the above numbered patent requiring correction as follows: Page 3, lines 76 and 77, claim 1, strike out the words "comprising a stiff cover extensible angularly and"; and that the said Letters Patent should be read with this correction therein that the same may conform to the record of the case in the Patent Office.

Signed and sealed this 15th day of May, A. D. 1928.
